UNITED STATES PATENT OFFICE.

HENRY E. HALGRIMSON, OF PRESHO, SOUTH DAKOTA.

FENCE-POST ANCHOR.

Application filed August 3, 1928. Serial No. 297,136.

This invention relates to anchors for posts and the like and has for an object the provision of a device which may be secured to a post and the latter freely driven into the ground, the device providing effective resistance to outward movement of the post after the latter has been properly inserted.

Another object of the invention is the provision of a post anchor of simple and durable construction, being preferably made of sheet metal and including a pair of hingedly connected plates and stops, with the latter struck from the material of one of the plates.

With the above and other objects in view, the invention further includes the following novel features and details of construction, to be hereinafter more fully described, illustrated in the accompanying drawings and pointed out in the appended claims.

20 In the drawings:

Figure 1 is an elevation of a fragmentary portion of a fence post with the invention applied, the hinged plate being positioned for insertion into the ground.

25 Figure 2 is an elevation at right angles to Figure 1.

Figure 3 is a top view.

Figure 4 is a section on the line 4-4 of Figure 1.

30 Figure 5 is a view similar to Figure 1 showing the hinged plate in its lowermost position.

Figure 6 is an elevation at right angles to Figure 5.

35 Referring to the drawings in detail wherein like characters of reference denote corresponding parts, the reference character 10 indicates a portion of a fence post which is preferably made of metal and which may be 40 T shaped as shown in the drawings. The lower end of this post is inclined as at 11 so as to provide a sharpened point for insertion into the ground.

The invention includes an attaching plate 45 12 which is secured to one face of the post and for this purpose, the post may be provided with laterally disposed spaced lugs 13 for insertion in openings 14 provided in the plate 12 and these lugs may be upset so that 50 the plate 12 will be riveted to the post. The opposite side edges of the plate 12 are preferably upwardly and outwardly inclined as shown at 15 so as to facilitate entrance of the plate into the ground.

55 Hingedly secured to the upper edge of the attaching plate 12, preferably by means

of rings 16, is a plate 17. This last mentioned plate is provided with spaced openings 18 so that the plate may assume the position shown in Figures 1 and 2 of the drawings. 60 In this position, the plate 17 lies flat against the face of the post and the openings 18 are for the purpose of accommodating the spaced lugs 13 so as to permit of this position of the plate. 65

As the post is driven into the ground, the plate 18 assumes the position shown in Figures 1 and 2. Any attempt to pull the post upward will be resisted by the plate 17 as upward movement of the post will cause this 70 plate to move outward and downward. This movement is insured by providing the plate 17 along its upper edge with outturned corners 19 which will act to guide the plate outward or away from the post as the latter 75 moves upward.

Downward movement of the plate 17 with respect to the post is limited by stop wings 20. These wings are preferably formed by slitting the plate 12 downwardly and inwardly as shown at 21 and bending the material adjacent these slits laterally with respect to the plate so that outwardly extending tapered stop wings are provided. The tapered wings form a minimum amount of resistance 80 to the entrance of the post into the ground. 85

The invention is susceptible of various changes in its form, proportions and minor details of construction and the right is herein reserved to make such changes as properly fall within the scope of the appended claims. 90

Having described the invention what is claimed is:

1. In combination with a post, an anchor comprising an attaching plate adapted to lie flat against a vertical face of the post, means to secure the plate to the post, a plate having one of its edges hingedly secured to the upper edge of the attaching plate, said hingedly secured plate being adapted to lie parallel 95 with the post as the latter is inserted into the ground, and to assume an angular position when the post is pulled outward, means included in the hinged plate to initially resist upward movement, and means to limit independent downward movement of the hinged plate. 100

2. In combination with a post, an anchor comprising an attaching plate adapted to lie flat against a vertical face of the post, means to secure the plate to the post, a plate having one of its edges hingedly secured to the up- 105 110

per edge of the attaching plate, said hingedly secured plate being adapted to lie parallel with the post as the latter is inserted into the ground and to assume an angular position when the post is pulled outward, outwardly curved corners provided upon the outer edge of the hinged plate to initially resist upward movement, and means to limit independent downward movement of the hinged plate.

10 3. In combination with a post, an anchor comprising an attaching plate adapted to lie flat against a vertical face of the post, oppositely and outwardly inclined side edges for said plate, means to secure the plate to the post, a plate having one of its edges hingedly secured to the upper edge of the attaching plate, said hingedly secured plate being adapted to lie parallel with the post as the latter is inserted into the ground and to assume an angular position when the post is pulled outward, means included in the hinged plate to initially resist upward movement, and means to limit independent downward movement of the hinged plate.

15 20 4. In combination with a post, an anchor comprising an attaching plate adapted to lie flat against a vertical face of the post, means to secure the plate to the post, a plate having one of its edges hingedly secured to the up-

per edge of the attaching plate, said hingedly secured plate being adapted to lie parallel with the post as the latter is inserted into the ground, and to assume an angular position when the post is pulled outward, means included in the hinged plate to initially resist upward movement, and outwardly disposed tapered wings struck from the attaching plate and arranged in the path of downward movement of the hinged plate to provide stops.

25 30 35 40 45 50 55 4. In combination with a post having spaced laterally extending lugs, an anchor comprising an attaching plate having openings therein to receive the lugs to provide means for securing the plate to the post, a plate having one of its edges hingedly secured to the upper edge of the attaching plate and also having openings to receive said lugs to permit the hinged plate to lie parallel against the face of the post as the latter is inserted into the ground and to assume an angular position when the post is pulled outward, means included in the hinged plate to initially resist upward movement, and means to limit independent downward movement of said hinged plate.

In testimony whereof I affix my signature.

HENRY E. HALGRIMSON.
